UNITED STATES PATENT OFFICE.

HOBERT J. HURD, OF BRIDGEPORT, CONNECTICUT.

WAD-PRINTING MACHINE.

No. 800,742.

Specification of Letters Patent.

Patented Oct. 3, 1905.

Application filed February 11, 1904. Serial No. 193,080.

To all whom it may concern:

Be it known that I, HOBERT J. HURD, a citizen of the United States, and a resident of Bridgeport, in the county of Fairfield and State 5 of Connecticut, have invented certain new and useful Improvements in Wad-Printing Machines, of which the following is a specification.

My invention relates to improvements in 10 machines for printing gun-wads on both sides; and it consists in certain details of construction to be more fully set forth in the following specification, and such features that are believed to be new and novel will be particularly 15 set forth in the claims.

To enable others to understand my invention, reference is had to the accompanying drawings, in which—

Figure 1 represents a side elevation of the 20 machine and broken view of its standard and wad-feeding mechanism. Fig. 2 is an upper plan view of the machine. Fig. 3 is an enlarged central sectional view of the gear, having a cam on its vertical face adapted to actuate 25 the vertically-operating slides pertaining to the printing mechanism, sectional view of said slides, enlarged view of the upright, and sectional view of the wad-magazine through line *a* of Fig. 2. Fig. 4 is an enlarged broken 30 sectional view of the support on which the cam-gear actuating the slide of the printing mechanism rotates through line *b b* of Fig. 3, also upper plan view of the wad-feeding mechanism. Fig. 5 is an enlarged detail view 35 of the distributing and inking rolls, broken view of the inking-pads, broken view of the type-carriers, and sectional view of the ink-fountain. Fig. 6 is an enlarged upper plan view of one of the distributing-rolls and one 40 of the inking-rolls and frame for same. Fig. 7 is an upper plan view of the wad-feeder and broken view of its supporting-bracket, showing the method of feeding the wads. Fig. 8 is a similar view showing wads of smaller 45 diameter being fed.

Its construction and operation are as follows:

1 is the standard of the machine; 2, the bed. 50 3 is the driving-shaft, carrying the hand-wheel 4, tight pulley 5, and loose pulley 6. The shaft 3 is journaled in the bracket 7, secured to the upright 8. 9 is a pinion on said shaft registering with the large gear 10, Figs. 1 and 3. This gear is rotatably mounted on

the hollow journal 8^a of the frame 8 and is 55 provided with the cam-groove 11 on its vertical face to receive the rolls 12 and 13, which rolls are mounted on the head of the screws 14 and 15, secured to the vertically-operating slides 16 and 17. 18 and 19 are housings projecting from these slides, which slides carry the adjustable shells 20 and 21, and their threaded ends carry the nuts 22 to adjust the vertical position of these shells. 23 and 24 are type-carriers mounted in said shells, the reduced 60 portions 23^a and 24^a passing through the ends of said shells. 25 and 26 are adjusting-nuts mounted on said threaded portions for the purpose of adjusting a spring placed between a shouldered portion of the type-carrier and 65 the ends of the shells. One of said springs 27 is shown at Fig. 3. These springs permit the type-carriers to react or give back slightly under the printing blow.

28 and 29 are type mounted in the inner 70 ends of the type-carriers.

The worm or screw wad-feeder consists of the body portion 30, having the coarse thread 30^a. This feeder is rotatably mounted in the adjustable box 31 and is intermittently rotated through the medium of the driving-shaft 3 as follows: 32 is a plate, Figs. 1 and 2, mounted on the end of said shaft, and it carries the screw 33. 34 is a connecting-rod having one end pivotally supported on this 80 screw and its other end on the screw 35 of the arm 36. The hub portion 36^a of this arm is journaled on the screw 37, projecting from frame or upright 8. 38 is a pawl pivotally supported on the arm 36, adapted to engage 85 with the notched plate 39 of the gear 40, rotatably mounted on the stud or screw 37. This gear meshes with the pinion 41 of the wad-feeder to effect an intermittent rotary movement of said feeder through the medium of 90 the mechanism just described.

42 and 43 are ink-fountains having a longitudinal adjustment (see also Fig. 5) through the medium of the elongated holes 44 and 45, embracing the side clamping-screws 46 and 100 47. 48 and 49 are fountain-rolls journaled on the pins 50 and 51 in the end of said ink-fountains.

52 and 53 are ink-scrapers adapted to be 105 adjusted to and from the fountain-rolls by means of the adjusting-screws 54 and 55 (see also Figs. 1 and 2) to remove surplus ink from the surface of said rolls. These rolls

are intermittently rotated as follows: 56 is a cam-plate mounted on the shaft 3 and has on its outer periphery the projection 56^a to engage with the roll 57, mounted on the lower 5 end of the vertical link 58. 59 and 60 are arms carrying the pawls 61 and 62, adapted to engage with the ratchet-wheels 63 and 64, secured to the pins 50 and 51 of the fountain-rolls. One end of the said arms is journaled on the said pins and the other end on the screws 65 and 66 of the link 58.

67 and 68 are the inking-pads secured to the frame or upright 8 and are vertically adjustable thereon.

15 69, Fig. 1, is a reciprocating slide adapted to operate through the medium of the lever 71, whose upper end carries the link 72, connected to said slide. The lower end of this lever is journaled on the pin 73, projecting 20 from the bed of the machine, while intermediate of the ends of this lever is the roll 74, adapted to engage with the cam-groove in the inner vertical face of the cam-plate 56.

Referring to Fig. 5, 76 is a stud projecting 25 from the slide 69, and 77 and 78 are levers pivotally supported on this stud. 79 and 80 are frames pivotally supported on the outer ends of these levers, and 81 and 82 are the ink-distributing rolls, and 83 and 84 are the 30 inking-rolls journaled in said frames. 85 is a spring-clip engaging the inner ends of said levers, so as to apply an outward pressure to said rolls. 86 is an adjusting-screw to regulate such pressure. The reciprocating movement of the slide will bring the distributing-rolls against or in close proximity to the rotatable fountain-rolls on each backward movement of the slide, and the amount of ink taken up by these distributing-rolls is determined 35 by the closeness of this proximity and the amount of ink carried by the fountain-rolls. The forward movement of the slide will cause the rolls 81 and 82 to distribute the ink evenly onto the surface of the inking-pads, so that the inking-rolls 83 and 84 will take up the necessary amount of ink for the type as said rolls pass over the pads.

87, Figs. 1, 2, 3, and 4, is the gravity-feeding wad-magazine, which is filled with the unprinted wads 88. The magazine overlies an opening in the cap 89 of the box 31, with its foot secured to the side of said box. The wads drop from the magazine one at a time onto the cylindrical body portion of said feeder and between the threads, and they are kept from rotating or turning with the feeder by reason of the engagement of their edges with the channel-way 89^a, formed on the under surface of the caps 89. As fast as one wad passes 55 from under the magazine another takes its place and is in turn fed on toward the type in one continuous succession.

90, Figs. 3 and 4, is an interchangeable die-plate located at the forward end of the wad-feeder, having the hole 91 to admit the upper

and lower type. This plate is also provided with the channel-way 92 to guide the wads centrally with respect to the type. As soon as a wad is printed it is pushed out of the range of the type by the next incoming wad 70 delivered from the feeder. The printed wads are forced along the block 93, extending through the hollow journal 8^a, and are delivered at its end, as shown at Fig. 4. This block has the overlying caps 94, which caps 75 also have the channel-way 95.

The great advantage of the worm or screw feeder over a dial-feeder rotating in a horizontal plane, where the wads are fed into holes circumferentially arranged in said dial, is the 80 less number of parts required, more accurate delivery of the wads to the type, and the necessity avoided of changing the size of the worm or screw feeder for different sizes of wads, which is necessary where a dial-feed is 85 used.

The pitch of the screw or space between the threads, Fig. 7, is made to receive wads of the greatest diameter required. The central portion between the threads will of course be central with the center of the magazine, so that when a large-sized wad is deposited on the feeder it will about fill the space between the threads 30^a. The main determining factor, however, in securing correct feeding is the 95 engagement of the right-hand face of the threads with the edge of the wads, for it is this face that engages with the edges of the wads to move them forward, and therefore the location of the edge of the wads with this 100 face is very important.

The placing of the wads between the type so that their center (represented by the line c) shall lie central with the type is determined by the extreme end 30^b of the thread. In 105 other words, the distance between the extreme end 30^b of the thread and the center of the type is equal to one-half the diameter of the wad being fed, so that when the wad is between the type the thread portion of the 110 screw-feeder exerts no further pushing influence on the wad, and when the wad so located is printed another wad is fed along, as before mentioned, to push the printed wad away from the type and take its place.

All that is necessary in printing wads of smaller diameter is to change the die-plate 90 for one having a channel-way which equals the diameter of the wad to be printed and move the box 31, in which the screw-feeder is journaled, forward, as follows: 96, Fig. 8, is a bracket integral with the upright 8 and is provided with the elongated holes 97 for the screws 98, which screws are attached to the box 31. When, therefore, smaller wads are 120 printed, this box is loosened and moved forward against the die-plate. When a small wad drops onto the body portion of the screw-feeder, it will lie midway of the threads; but as it cannot rotate with the feeder it will re- 130

main stationary for an instant until the thread has caught up and engaged its edge to push it forward.

Whatever position the box 31 occupies, the 5 end 30^b of the thread of the screw-feeder must always stand from the center of the type a distance equal to one-half the diameter of the wads that are being printed. This position can be accurately and quickly determined 10 by means of the lines or scale *h* on the bracket and box, or, Figs. 3 and 4, the distance from the edge *i* of each die plate or block to the center of its type-hole 91 equals one-half of the diameter of the wad intended 15 to be used with said die-plate.

To counteract the wear of the cam-groove 11 and the rolls of the slides which operate therein, I employ the adjusting-screws 99 and 100, Fig. 3, whose points are adapted 20 to engage with the enlarged portion 8^b of the hollow journal 8^a when the type engages with a wad. This makes a positive limiting-point for the inward travel of the type.

Another great advantage of the screw-feeder over the dial-feed lies in the fact that if through the carelessness of the operator the magazine should become empty there will always be a wad between the type to prevent the type-faces coming in direct contact with 30 each other.

The machine above described is not only cheap and simple of construction and containing but few parts, but it is absolutely correct and accurate in its operation and is capable 35 of printing more wads in a given length of time than can be done by a machine using a dial-feed.

Having thus described my invention, what I claim is—

1. The combination, in a wad-printing machine, comprising a bed, a driving-shaft carrying a gear, a gear journaled on a stationary support to mesh with the gear on the driving-shaft, slides carrying type said slides movable 45 to and from the axial line of said support, a single cam to operate both of said slides for the purpose set forth.

2. The combination, in a wad-printing machine, comprising a driving-shaft carrying a 50 driving-gear, a gear meshing therewith and journaled on a stationary support, said gear having a cam-groove in its vertical face, type-carrying slides operatively connected with said cam-groove to reciprocate the type to 55 and from the center of said stationary support, for the purpose set forth.

3. The combination, in a wad-printing machine, comprising reciprocating slides carrying printing-type, a magazine for holding 60 the unprinted wads, an intermittently-rotatable screw underlying the magazine to receive the wads and carry them to the type, for the purpose set forth.

4. The combination, in a wad-printing machine, comprising reciprocating printing-

type, a magazine for holding unprinted wads, an intermittently-rotatable wad-feeding screw adapted to receive wads from the magazine and deposit them in the printing-line of the type, for the purpose set forth. 70

5. The combination, in a wad-printing machine, comprising a frame, a cam rotatably mounted on a hollow journal, type-carrying slides actuated by said cam to and from the center of said journal, a wad-magazine, a screw wad-feeder for said wads underlying the magazine, a channel-way through which the wads are fed by said screw toward the type, said feeder adapted to be longitudinally adjusted with respect to the type so that, the 80 distance from the end of the thread of said feeder to the center of the type will equal one-half the diameter of the wads being fed, a die-plate having a hole therethrough for the type and a channel-way for the wads, a discharge channel-way for the printed wads extending from said die-plate through said hollow journal, an ink-fountain, and inking-rolls, for the purpose set forth. 85

6. The combination, in a machine for printing wads, comprising a magazine, an intermittently-rotatable wad-feeding screw adapted to receive the wads from the magazine, reciprocating type, an interchangeable die-plate in the pathway of the type, means for guiding 95 the wads to said die-plate, and means for guiding and centralizing the wads therein, for the purpose set forth. 90

7. The combination, in a machine for printing wads, comprising an intermittently-rotatable wad-feeding screw, an overlying wad-magazine adapted to discharge wads upon said screw-feeder, a die-plate in advance of said feeder, type adapted to reciprocate to and from said die-plate, a guide or channel way 100 in said die-plate and also in close proximity to said feeder, said feeder having a longitudinal adjustment to and from the type so that, the distance from the discharge end of the thread of said feeder and the center of the 105 type will equal one-half the diameter of the wads being fed. 110

8. The combination, in a machine for printing wads, comprising a wad-feeding screw, reciprocating type, a die-plate in the line of the 115 type, the distance from the edge of said plate to the center thereof being equal to one-half the diameter of the wads being fed, for the purpose set forth.

9. The combination, in a machine for printing wads on both sides, comprising reciprocating type, ink-fountain, inking-rolls, wad-feeding magazine and a screw-feeder for said wads, which feeder is adapted to receive the wads from the magazine and deposit them one 120 at a time in the printing-line of the type, the distance from the discharge end of the thread of said feeder and the center of the type being equal to one-half of the diameter of the wads being fed, for the purpose set forth. 125

10. The combination, in a machine for printing wads, comprising a wad-feeding magazine, reciprocating type, an intermittently-rotatable screw adapted to receive the wads from the magazine and carry them forward to the type, for the purpose set forth.

11. The combination, in a machine for printing wads, comprising a bed, a driving-shaft carrying a driving-gear, a cam and gear actuated by said driving-gear, a hollow journal projecting from said bed for said cam and gear, reciprocating slides carrying type actuated by said cam to and from the center of said journal, a wad-feeding magazine, a screw-feeder to receive the wads therefrom and deposit them between the type, a channel-way for the wads between the magazine and type, means for delivering the printed wads from the type through the hollow journal, for the purpose set forth.

12. In a wad-printing machine, a cam, a hollow support on which said cam is journaled, type-printing mechanism carrying type, said

mechanism actuated by said cam, a wad-feeding magazine, means for conveying the wads from said magazine to the type and discharging the printed wads through said hollow support, for the purpose set forth.

13. In a wad-printing machine of the character described, a cam, a hollow support on which said cam is journaled, type-printing mechanism carrying type, said mechanism actuated by said cam, inking-rolls, ink-distributing rolls, ink-fountain, inking-pads, a wad-feeding magazine, a wad screw-feeder to carry the wads from the magazine to the type and cause them to be discharged through said hollow support, for the purpose set forth.

Signed at Bridgeport, in the county of Fairfield and State of Connecticut, this 30th day of January, A. D. 1904.
